(57) **CLAIM**

The ornamental design for a nougat, as shown and described.

DESCRIPTION

1. Nougat

2. Nougat

Figure 1.1 is a front, top and right side perspective view of a first embodiment of a nougat showing my new design;

Figure 1.2 is a rear elevation view thereof;

Figure 1.3 is a right side elevation view thereof;

Figure 1.4 is a top plan view thereof;

Figure 1.5 front elevation view thereof;

Figure 1.6 is a left side elevation view thereof;

Figure 1.7 is a bottom plan view thereof;

Figure 2.1 is a front, top and right side perspective view of a second embodiment of a nougat showing my new design;

Figure 2.2 is a rear elevation view thereof;

Figure 2.3 is a right side elevation view thereof;

Figure 2.4 is a top plan view thereof;

Figure 2.5 front elevation view thereof;

Figure 2.6 is a left side elevation view thereof; and

Figure 2.7 is a bottom plan view thereof.

The stippled shading and unshaded areas shown in Figures 1.1–2.7 represent a contrasting appearance.
